UNITED STATES PATENT OFFICE.

CARLETON B. HUTCHINS, OF DETROIT, MICHIGAN.

WALL FOR REFRIGERATOR-CARS.

SPECIFICATION forming part of Letters Patent No. 337,770, dated March 9, 1886.

Application filed September 29, 1885. Serial No. 178,530. (No model.)

To all whom it may concern:

Be it known that I, CARLETON B. HUTCHINS, a citizen of the United States, residing in Detroit, in the county of Wayne and State 5 of Michigan, have invented a new and useful Improvement in Walls for Refrigerator-Cars, of which the following is a specification.

In refrigerator-cars, and especially in those of that class wherein the ice chamber or pan is located at the top of the car, nearly the whole 10 load is unsupported from the top, as the carcasses are suspended from above, and consequently the car is subjected to peculiar strains, which tend to loosen the joints and render the walls 15 pervious to the air, and therefore a wall structure of great strength and rigidity is required. The frame-work, however, heretofore ordinarily employed divides the space between the double walls into small compartments, thus not 20 only rendering it difficult to pack the insulating material therein, but creating a large number of joints or crevices where the insulating material bears against the dividing frame-work, whereby the insulating character of the walls 25 is rendered much more defective.

The object of the present invention is to provide a strong, simple, cheap, and durable construction of double walls for refrigerator-cars without the necessity of using any framing or studding, so that the non-heat-conducting or insulating material may be properly and conveniently packed between the inside and outside walls, and also form a continuous insulating sheath or protection all around the 30 car not broken or interrupted by any frame-work.

This result I secure, and herein my invention consists, by inner and outer walls, each composed of two layers of matched boards, the 35 boards of each layer being arranged diagonally or to cross those of the other layer, and the two layers being nailed or otherwise firmly secured together, so as to brace each other. Sheets of paper, felt, or other like insulating 40 material may be interposed between the two layers of diagonal matched boards, and the outside wall is lined upon the outside with matched boards extending vertically, while the inside wall is similarly lined upon the 45 inside. This layer of vertical boards, in combination with the two layers of diagonal boards

of each wall, adds greatly to the strength and rigidity of the structure, especially to sustain vertical pressure or strains, and also materially increases the insulating character of the 55 walls. Sheets of felt or paper or other insulating or impervious material should be interposed between the vertical and diagonal layers of boards. The outer sills or timbers of the platform or bottom frame-work of the car are 60 provided with offsets or shoulders at each side, upon which rest the ends of one of the layers of diagonal boards, while the other layer is slightly longer and fits against the side of the sills, to which it is securely spiked or otherwise secured. Vertical tie-rods extend from the sills to the top of the car, between the inner and outer walls, and cross tie-rods extend 65 between the two side walls of the car.

In the accompanying drawings, which form 70 a part of this specification, and in which similar letters of reference indicate like parts, Figure 1 is an end view, partly in cross-section, of a refrigerator-car embodying my invention, the layers of vertical boards upon 75 the outside and inside of the car being also in part removed to show the layers of diagonal boards; and Fig. 2 is a partial longitudinal section.

As the present invention does not relate to 80 the interior parts of the refrigerator-car, the same have been omitted from the drawings.

In said drawings, A represents the sills or platform frame-work of the car, which may be of any ordinary construction, and B and C 85 are the outer and inner walls, which form the double walls of the car. The walls B C consist of two layers of matched boards, b c and b' c', arranged diagonally or crossing each other, preferably at an angle of about sixty 90 degrees, and securely nailed together. The two inner or adjacent layers of boards, b c, are somewhat shorter than the outer ones, b' c', thus forming an offset or shoulder on each wall B C, and the outside sills, A, are provided at each side with corresponding offsets or shoulders, a a', so that the ends of the boards b c, fitting in the offsets a a', will rest upon the sills A, while the longer boards, b' c', will fit against the sides of the sills, to which 95 they are securely nailed or spiked. By this 100 means a very strong and rigid connection is

afforded between the walls B C and the platform or sills of the car, especially to withstand vertical and racking strains, as each one of the diagonal boards is a separate brace. The space between the walls B C should be about three inches, and is packed with a non heat-conducting or insulating material, D, preferably consisting of wool, wool waste, or woolen rags cut into fine shreds or pieces. As there is no studding or frame-work between the walls, the insulating material may be easily and thoroughly packed in, and will form a continuous protecting-sheath all around the car. Vertically-extending matched boards b^2 c^2 are nailed or otherwise secured upon the outside of the wall B and the inside of the wall C, and serve to both strengthen the walls and improve the insulation. Layers of paper, felt, or other insulating or impervious material, b^3 c^3 and b^4 c^4 , are inserted between the diagonal boards b and b' , c and c' , and between the vertical boards b^2 c^2 and the diagonal boards b' c' . Stays or braces d, preferably consisting of wood-screws fitting in suitable screw-threaded holes made in the walls B C, serve to brace and bind said walls firmly together, and render the whole structure firm and rigid as one solid wall. Cleats a^2 are secured to the sides of the longitudinal sills A, upon which rest the floor-boards a^3 . Insulating material D is then packed in, and the cross floor-boards a^4 laid down thereon, so as to be flush with the upper surface of the sills. The longitudinal floor-boards a^5 and a^6 are then laid down. Sheets of paper, felt, or other like material, a^7 , should be interposed between the boards a^3 and a^6 . The edges of the floors a^5 and a^6 extend out and fit against the diagonal wall-boards c' , so that the ends of the vertical boards c^2 will rest upon said floor. In this way it will be seen that the inner and outer layers, c c^2 , rest with their ends upon the platform or floor of the car, while the intermediate layer, c' , extends down flush with the bottom edge of the sills A. This inner wall is thus adapted to withstand great vertical pressure, and to sustain the beams which support the ice-chamber, and from which the load of meat is suspended. The cross-beams E, which support the roof, extend through and rest upon the opposite inner side walls of the car.

e e' e^2 represent the several layers of matched boards constituting the roof of the car, with the insulating material D and paper, felt, or roofing composition e^3 e^4 between them.

In each of the four corners of the car a triangular upright post, H, is secured to the inside walls, C, by suitable screws or nails, to give additional strength and rigidity to the structure. Tie-rods F extend from the top of the walls B C through the bottom sills, A, of the car in the space between the walls, and cross tie-rods G extend horizontally between and are anchored in the opposite side walls of the car. Vertical angle-plates N are provided at each corner of the car upon the outside of the walls B, but inside the vertical layer of boards

b^2 , to support and strengthen the car at its corners.

I claim—

1. The double wall for refrigerator-cars, consisting of an inner and an outer wall, each composed of two layers of boards arranged diagonally to or crossing each other, and a non-heat-conducting or insulating material 75 filling the space between said walls, substantially as specified.

2. The double wall for refrigerator-cars, consisting of an inner and an outer wall, each composed of two layers of matched boards 80 arranged diagonally to or crossing each other, the outside wall having a layer of vertically-arranged matched boards upon its outside, and the inner wall having a layer of vertically-matched boards upon its inside, and a non-heat-conducting or insulating material in the space between said walls, substantially as specified.

3. The combination, in a refrigerator-car, with the outside sills, A, having shoulders or 90 offsets a a' , of the frameless outer wall, B, consisting of diagonally-arranged boards b b' , the inner layer of boards, b , being shorter than the layer of outer boards, b' , to form a shoulder or offset corresponding to the shoulder a 95 on the sill, an inner frameless wall, C, consisting of diagonally-arranged boards c c' , the boards c being shorter than the boards c' , to form an offset or shoulder corresponding to offset or shoulder a' on the sills, and an insulating material, D, between said walls, substantially as specified.

4. The combination, in a refrigerator-car, with the outside sills, A, having shoulders or 105 offsets a a' , of the frameless outer wall, B, consisting of diagonally-arranged boards b b' , the inner layer of boards, b , being shorter than the layer of outer boards, b' , to form a shoulder or offset corresponding to the shoulder a on the sill, an inner frameless wall, C, consisting of diagonally-arranged boards c c' , the boards c being shorter than the boards c' , to form an offset or shoulder corresponding to offset or shoulder a' on the sills, and an insulating material, D, between said walls, a layer 110 of vertically-arranged boards, b^2 , upon the outside of the outer wall, and a layer of vertically-arranged boards, c^2 , upon the inside of the inner wall, substantially as specified.

5. The double wall for refrigerator-cars, 120 consisting of an inner and an outer wall, each composed of two layers of matched boards arranged diagonally to or crossing each other, the outside wall having a layer of vertically-arranged matched boards upon its outside, 125 and the inner wall having a layer of vertically-matched boards upon its inside, and a non-heat-conducting or insulating material in the space between said walls, said layer of diagonal boards having sheets of paper, felt, or like 130 insulating material interposed between them, substantially as specified.

6. The double wall for refrigerator-cars, consisting of an inner and an outer wall, each

- composed of two layers of matched boards arranged diagonally to or crossing each other, the outside wall having a layer of vertically-arranged matched boards upon its outside, 5 and the inner wall having a layer of vertically-arranged matched boards upon its inside, and a non-heat-conducting or insulating material in the space between said walls, said layers of diagonal boards having sheets of paper, felt, 10 or like insulating material interposed between them, and sheets of paper, felt, or like insulating material interposed between said layers of vertically and diagonally arranged boards, substantially as specified.
- 15 7. The combination, with the platform or bottom frame of the car, of double walls resting thereon, consisting of an inner and an outer frameless wall, each composed of two layers of diagonally-arranged or crossing boards, an insulating material between said walls, and tie-rods extending from the top of said wall to the bottom of said platform or bottom frame, 20 and horizontal cross-rods extending between and anchored in the opposite side walls of the car, and the cross-beams of the roof extending between and resting upon the opposite side walls of the car, substantially as specified.
8. The combination, with the platform or bottom frame of the car, of double walls resting thereon, consisting of an inner and an outer 25

frameless wall, each composed of two layers of diagonally-arranged or crossing boards, an insulating material between said walls, and tie-rods extending from the top of said wall to the bottom of said platform or bottom frame, 30 and horizontal cross-rods extending between and anchored in the opposite side walls of the car, substantially as specified.

9. The combination, with the platform or bottom frame of the car, of double walls resting thereon, consisting of an inner and an outer frameless wall, each composed of two layers of diagonally-arranged or crossing boards, an insulating material between said walls, and tie-rods extending from the top of said wall to the bottom of said platform or bottom frame, 35 and horizontal cross-rods extending between and anchored in the opposite side walls of the car, and the cross-beams of the roof extending between and resting upon the opposite side walls of the car, substantially as specified. 40
